US0D1014572S

(12) **United States Design Patent** (10) Patent No.: **US D1,014,572 S**
(45) Date of Patent: ** Feb. 13, 2024

(54) **CONSTRUCTION MACHINE**

(71) Applicant: **Volvo Construction Equipment AB**,
Eskilstuna (SE)

(72) Inventors: **Roland Schling**, Torslanda (SE);
Viktor Holmqvist, Gothenburg (SE);
Gustavo Guerra, Gothenburg (SE)

(73) Assignee: **VOLVO CONSTRUCTION
EQUIPMENT AB**, Eskilstuna (SE)

(**) Term: **15 Years**

(21) Appl. No.: **29/890,582**

(22) Filed: **Apr. 25, 2023**

(57) **CLAIM**

The ornamental design for a construction machine, as shown and described.

DESCRIPTION

FIG. 1 is a rear, top, left side perspective view of a construction machine embodying our new design;

FIG. 2 is a rear, top, right side perspective view thereof;

FIG. 3 is a rear view thereof;

FIG. 4 is a left side view thereof;

FIG. 5 is a right side view thereof; and,

FIG. 6 is a top view thereof.

The broken lines and greyed out areas inside the broken lines represent portions of the construction machine that form no part of the claimed design.

1 Claim, 6 Drawing Sheets
